Attorney

UNITED STATES PATENT OFFICE

GRAHAM C. WOODRUFF, OF BRONXVILLE, NEW YORK, ASSIGNOR TO THE L. C. L. CORPORATION, A CORPORATION OF DELAWARE

BOTTOM LIFT CONTAINER

Application filed August 25, 1932. Serial No. 630,475.

This invention relates to containers for container cars and to means for lifting the same for transfer to and from the car. More particularly the invention relates to containers of the crane-lift type and to improved lifting means for use in connection therewith.

Containers of this type are generally made of sheet metal and provided at the top, generally at the corners, with links or like engaging members for connection with the crane lift chains or tackle. Such containers are, therefore, lifted from the top and, in order that the lifting strains may be properly distributed, and buckling of or other damage to the container prevented, it is necessary not only to strongly brace the container but to use comparatively heavy material in its construction, so that such containers are of much greater strength and weight than necessary for them to otherwise be.

The main object of the present invention is to provide novel and improved lifting means for the container, whereby the container may be lifted from the bottom instead of from the top, thus enabling the weight of the container and its load to be sustained without throwing undue strain upon any part of the container, and thereby enabling a container for any given purpose of lighter weight and less cost to be produced.

A further object of the invention is to provide a simple, reliable and efficient construction of lifting means of the character and for the purpose specified.

The invention consists of the features of construction, combination and arrangement of parts, hereinafter fully described and claimed, reference being had to the accompanying drawings, in which:—

Fig. 1 is a top plan view of a container embodying my invention.

Fig. 2 is an end elevation of the same.

Fig. 3 is a vertical section through one end of the container showing the application of one of the lifting chains.

Fig. 4 is a fragmentary end elevation of the container on an enlarged scale showing the application of one of the lifting chains.

Fig. 5 is a view showing more particularly the construction of the spreader.

Fig. 6 is a top plan view of the container and spreader in place.

Referring now more particularly to the drawings, 1 designates a container of that type adapted for use on container cars and which, in practice, may be made of any suitable size and of rectangular or oblong rectangular form, a container of oblong rectangular form being shown in the present instance. The container is shown as having side walls 2, end walls 3, a top wall 4 and a bottom wall 5. The walls 2, 3 and 4 and the wall 5 also, if desired, may be made of sheet metal of suitable gage or thickness. The container may be provided in practice with any suitable type of door or other closure means and may carry upon certain of its walls, as the walls 2, guiding and retaining shoes 6 for guiding the container into and out of a container car and holding it therein in spaced relation to adjacent containers.

Generally a container of this character is provided upon its top wall, in the region of its corners, with stay plates carrying links or like engaging members for connection of the lifting chains or tackle of the crane therewith. In the present instance the use of such top links or engaging members is dispensed with, but the container top is provided in lieu thereof with corner stays 7 having outwardly projecting portions 8 extending laterally beyond the walls and provided with grooved or channeled retainers 9, preferably flared at their lower ends, as indicated at 10. These retainers 9 are adapted for the reception and retention in position of the four lifting chains 11 commonly employed which are united at their upper ends by a ring or link or other like element 12, whereby the lifting chains or tackle may be connected with the crane hoist. Then chains when in engagement with the container depend along the walls 3 thereof and are provided at their lower free ends with engaging hooks 13 for connection with engaging links, rods or members 14 on the base or bottom of the container, whereby the container and its load may be supported

and lifted from its bottom instead of be-

- ing supported and lifted from its top, in the customary way, thereby relieving the top of the container and adjacent portions of the walls from the weight of the load 5 and properly distributing the load weight and lifting strains so as to avoid any liability of buckling or other damage to the container during the lifting action. By this means the walls of the container may be made of 10 lighter metal, and the use of wall braces wholly or largely dispensed with, enabling a container of lighter weight for any given purpose to be made at less cost and having other resulting advantages.
- 15 The engaging members 14 are preferably arranged on the inside of the container walls 3 below the bottom wall 5, which is elevated to a desired degree, thus adapting the members 14 to be placed directly beneath the 20 bottom wall and within the bottom portion of the container where they will be securely housed and protected from injury. To permit of the engagement of the hooked ends of the grappling hooks 13 with the links or 25 engaging members 14 the walls 3 are provided in alignment with said engaging members 14 with openings 15 of a size to allow of the ready and convenient insertion and withdrawal of the hooks. In order to adapt the 30 chain engaging ends of the hooks to lie parallel and snugly in contact with the walls 3 when the hooked ends of the hooks are in engagement with the engaging members 14, the body portions of the grappling hooks are 35 preferably made L-shaped, so that their hooked ends and chain engaging arms lie substantially at right angles to each other. This construction adapts the hooked arms of the grappling hooks to be engaged with the 40 inner surfaces of the engaging members 14 and to be maintained in engagement therewith as long as the chains 11 are in operative position and taut, while, at the same time, admitting of the ready and quick release of 45 the hooks and chains by simply slackening the chains to a degree to adapt the relatively heavy or weighted chain engaging arms of the hooks to drop by gravity down to the dotted line position shown in Fig. 3, in which operation 50 the hooked ends of the hook will swing upwardly and outwardly on the engaging members 14 to a released position. This simple and effective construction and arrangement of the engaging hooks 13 and members 14 not only ensures the proper housing of the 55 members 14 from liability of injury, but also ensures the secure retention of the hooks in engagement with the members 14 as long as the chains are taut, as the chains will otherwise be held securely by the retainers 9 from 60 any possibility of displacement during raising, lowering and transfer movements of the container.
- 65 It will be understood, of course, that the retainers 9 and engaging members 14 may, if

desired, be placed upon the same walls as the guide shoes 6, but are preferably placed upon the container walls at right angles to the walls bearing the guide shoes, for greater convenience in applying and removing the chains where the shoes 6 are employed to more or less narrowly space the containers from each other. In the present instance the retainers 9 and engaging members 14 are placed upon the end walls of an oblong rectangular container which may be designed for use, for example, in a drop side container car, so that when the drop sides are down the chains may be applied or removed with great ease and facility. The bottom-lift attachments may, however, be applied upon square containers or containers of other desired forms and upon the same walls as the guide shoes or other walls as required to suit exigencies of service.

In order to enable the upper part of the container to be made of light weight, and to relieve the same from cushioning strains, a spreader 16, which is suitably supported, preferably from the link 12, is provided to engage the chains 11 at a suitable level above the container top 4 to hold the chains spread for such a distance above the top 4 of the container as to maintain the chains straight and vertical from the lifting points up to the spreader point, from which spreader points the chains may converge to the link 12. By this means the lifting pull is maintained in straight lines to a point sufficiently above the container to prevent any converging pressures from the corners 7 toward the center line of the container which would tend to crush and cause collapse of the container at its top. Hence the container may be made of comparatively light material throughout without liability of injury from lifting strains.

An important advantage of this invention, in addition to those stated, is that the bottom-lift avoids the necessity of employing what is known as a car rider, that is, a man to ride on the crane hook and stand on the top of the containers to engage the lifting chains with the links of a container as usually constructed.

While the construction disclosed is preferred, it will, of course, be understood that changes in the form, proportions, details of construction and arrangements of parts may be made within the scope of the appended claims, without departing from the spirit or sacrificing any of the advantages of the invention.

What I claim is:—

1. In a lift-type container, a container, attachable and detachable lifting means for the container arranged externally of the container and comprising lifting members extending from a point above the container to a point in proximity to the bottom of the container and having a detachable hook connec- 125

tion with the bottom portion of said container, retaining means for holding said members in retaining engagement with the upper portion of the container, means for connecting said lifting means with a hoisting device, and means engaging said members for holding the same spread above the top of the container to maintain the same and the lifting strains in straight lines.

10 2. In a lift-type container, a container, lifting gear for the container arranged externally of and attachable to and detachable from the container, means providing a detachable lift connection between the lower 15 end of the lifting gear and the lower end of the container, means at the upper end of the lifting gear above the container for connection with a lifting device, and retainers at the top of the container for removably 20 retaining the upper portion of the lifting means in connection therewith, said lifting means being movable laterally into and out of engagement with the retainers.

3. In lifting and transporting means for 25 containers of container cars, a container, a lifting and transporting means arranged externally of the container and embodying members having a detachable lifting connection with the container at the bottom of 30 said container, and retaining elements at the the top of the container with which said members are engageable and from which they are disengageable by relative lateral movements.

35 4. In a lifting and transporting means for containers of container cars, a container, a container lifting device for engagement with a lifting crane arranged externally of and comprising means attachable to and detachable from the container, said lifting device having means at its upper and lower ends for respective coupling engagement with a crane and the bottom of the container, and retaining elements on the upper portion of the 40 container for engagement with the lifting device between such ends by lateral movement of the members into or out of connection with said elements.

5. In lifting and transporting means for 50 lift-type containers of the character described, a container, slotted retaining members at or near the top of the container, keeper members at or near the bottom of the container, and a lifting device arranged externally of and attachable to and detachable from the container and comprising linear flexible members engageable intermediate their ends by relative lateral movements with said slotted retaining members and provided 55 at their lower ends with hooks for detachable engagement with said engaging means on the container, and means at the upper ends of the flexible members for connecting the same with a crane or the like.

6. In lifting and transporting means for

lift-type containers of the character described, a container having U-shaped retainers at or near its top and keepers at or near its bottom, a lifting device arranged externally of and attachable to and detachable from the container and comprising linear flexible members engageable intermediate their ends by lateral movement with the U-shaped retainers and having engaging hooks at their lower ends to detachably engage the keepers, means at the upper ends of said flexible members for suspending the lifting device from a crane or the like, and means for holding the flexible members spread above the containers to maintain the same and the lifting strains in straight lines.

7. In lifting and transporting means for lift-type containers of the character described, a container having channeled retainers at or near its top and keepers at or near its bottom, and a lifting device attachable to and detachable from the container and comprising linear flexible members engageable intermediate their ends with the retainers and having hooks at their lower ends to detachably engage the keepers, and means at the upper ends of said flexible members for suspending the lifting device from a crane or the like.

8. In lifting and transporting means for crane lift containers, a container having engaging members thereon at or near its bottom and forked retaining members thereon at or near its top, and a lifting device for suspending said container from a crane attachable to and detachable from the container and comprising linear flexible members adapted to be disposed vertically at opposite sides of the container and engageable with and disengageable from said retaining members by movements laterally with relation to the container, a coupling connecting said elements at their upper ends, and engaging members at the lower ends of said elements for detachable engagement with the engaging members on the container.

9. In lifting and transporting means for crane lift containers, a container having engaging members thereon at or near its bottom and forked retaining members thereon at or near its top, and a lifting device for suspending said container from a crane attachable to and detachable from the container and comprising chains adapted to be disposed vertically at opposite sides of the container and loosely and detachably engaged between their upper and lower ends with said retaining members, a coupling connecting said elements at their upper ends, and engaging members at the lower ends of said elements for detachable engagement with the engaging members on the container.

10. In lifting and transporting means for crane lift containers, a container having en-

gaging members thereon at or near its bottom and forked retaining members thereon at or near its top, said engaging and forked retaining members being arranged in pairs at opposite sides of the container and adjacent to the corners thereof, and a lifting device for suspending said container from a crane attachable to and detachable from the container and comprising linear flexible members 5 adapted to be extended downwardly at opposite sides of the container from a level above the top of the container to a level in the region of the bottom of the container and removably engaged between their upper and lower ends with said forked retaining members, a coupling connecting said lifting device at their upper ends, and engaging members at the lower ends of said elements for detachable engagement with the engaging 10 members on the container.

11. In lifting and transporting means for crane lift containers, a container having keepers thereon at or near its bottom and channeled retainers thereon at or near its top, said keepers and retainers being arranged at opposite sides of and in the region of the corners of the retainer, and a lifting device for suspending said container from a crane comprising two pairs of lifting members 15 adapted to be disposed vertically at said sides of the container and engaged with the channeled retainers thereon, a coupling connecting said lifting members at their upper ends and adapted for suspending the lifting device from a crane, and hooks at the lower ends of the lifting members to engage said keepers.

12. In lifting and transporting means for crane lift containers, a container having keepers thereon at or near its bottom and channeled retainers thereon at or near its top, said keepers and retainers being arranged at opposite sides of and in the region of the corners of the retainer, and a lifting device for suspending said container from a crane comprising two pairs of lifting chains adapted to be disposed vertically at said sides of the container and engaged with the channeled retainers thereon, a coupling connecting the 20 chains at their upper ends and adapted for suspending the lifting device from a crane, and hooks at the lower ends of the chains to engage said keepers.

13. In a lift type container, a rectangular sheet metal container, and lifting means for the container comprising engaging members at the bottom of the container in the region of the corners thereof, open sided retaining members at the top of the container in the 25 region of the corners thereof, and a lifting device attachable and detachable from the container and comprising linear flexible members extending downwardly alongside the container and laterally movable into and out of engagement with said retaining members

and provided at their lower ends with engaging elements for detachable engagement with said engaging members at the bottom of the container, and means at the upper ends of said flexible members for suspending the lifting device from a crane or the like. 70

14. In a lift type container, a rectangular sheet metal container, and lifting means for the container comprising engaging members at opposite sides of the bottom of the container in the region of the corners thereof, open sided retaining members at the top of the container in the region of the corners thereof, and a lifting device attachable and detachable from the container and comprising linear flexible members extending downwardly alongside the container and movable laterally into and out of engagement with said open retaining members and provided at their lower ends with engaging elements 75 engaging said engaging members at the bottom of the container, and means at the upper ends of said flexible members for suspending the lifting device from a crane or the like. 80

15. In a lift type container, a sheet metal container, and lifting means for the container comprising engaging members at the bottom of the container in the region of the corners thereof, retaining members at the top of the container in the region of the corners thereof, and a lifting device attachable to and detachable from the container and comprising linear flexible members extending downwardly alongside the container and loosely engaging said retaining members and provided at their lower ends with engaging elements 85 engaging said engaging members at the bottom of the container, and means at the upper ends of said flexible members for suspending the lifting device from a crane or the like. 90

16. In lifting and supporting means for crane lift containers, a container, keepers on the container adjacent to the bottom thereof, retainers on the container in the region of the top thereof, a lifting device embodying a draft element adapted to be disposed above the top of the container and flexible lifting elements depending therefrom and adapted to depend alongside the container and to detachably engage the retainers, means for connecting said lifting elements at their lower ends with the keepers at the lower portion of the container, and means for engaging and holding the lifting elements spread adjacent to and for a distance above the retainers and the top of the container to maintain the lifting strains in straight lines. 95

17. In a lift-type container, a container having inset engaging members in the region of its bottom adjacent to and lying within the plane of opposed vertical walls thereof, and attachable and detachable lifting means for the container comprising lifting elements adapted to be extended downwardly on the outside of said walls of the container from above the container to a point at or near the bottom of the container and having grappling hooks with shank portions and hook portions offset at substantially right angles to each other for quick detachable and pivotal connection with said inset engaging members of said container.

18. In a lift-type container, a container having inset engaging members in the region of its bottom adjacent to and lying within the plane of opposed vertical walls thereof, retainers on said walls of the container at or near the top of the container, and attachable and detachable lifting means for the container comprising lifting elements engageable and disengageable by lateral movements with and from the retainers and extended downwardly on the outside of said walls of the container

from above the container to a point at or near the bottom of the container and having means for detachable engagement with said inset engaging members of said container.

19. In a lift-type container, a container having opposed vertical walls provided with openings therein in the region of its bottom, keepers on the container adjacent to and lying on the inner sides of said walls in alignment with said openings, forked retainers on said walls of the container at or near the top of the container, and attachable and detachable lifting means for the container comprising lifting elements adapted to be detachably engaged with the retainers and extended downwardly on the outside of said walls of the container from above the container to a point at or near the bottom of the container and having grappling hooks formed with shank and hook portions offset substantially at right angles with each other for quick detachable and pivotal connection with said inset engaging members of said container.

In testimony whereof, I affix my signature.

GRAHAM C. WOODRUFF.
